CHAIR

Victor Leibo, Ridgefield Park, N. J.

Application August 16, 1933. Serial No. 684,484

8 Claims. (Cl. 155—127)

This invention relates to chairs, and particularly to what are known as high chairs and more particularly to the construction of the trays of chairs of this type; and the object of the invention is to provide means for mounting a tray so as to permit forward and backward sliding movement of the tray with respect to the chair and a pivotal or swinging movement of the tray to facilitate the placement of a child on the chair and the removal of a child therefrom; a further object being to provide a tray mounting of the class described which consists in providing the arms of the chair with guide rails and the tray with rods slidably engaging the rail with means for pivotally coupling the tray to the free ends of the rods; a further object being to provide means for limiting the swinging movement of the tray with respect to the rods; a further object being to provide latch devices for securing the tray in normal or closed position; a still further object being to provide, in conjunction with the tray, a retaining strap detachably coupled with the seat of the chair to prevent a child from slipping off the chair between the seat and tray; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a transverse sectional view through a chair made according to my invention and indicating the tray in closed and open positions.

Fig. 2 is a partial, sectional view on the line 2—2 of Fig. 1, showing parts of the construction broken away.

Fig. 3 is a sectional detail view similar to Fig. 1, with parts of the construction broken away and in section.

Fig. 4 is a partial section on the line 4—4 of Fig. 3; and,

Fig. 5 is an enlarged, sectional detail view similar to Fig. 2 on an enlarged scale, showing only a part of the construction and showing a modification.

For the purpose of illustrating one method of carrying my invention into effect, I have illustrated in Fig. 1 of the drawing an infant's high chair consisting of a seat 10, diverging legs 11, 55 joined by suitable bracing cross rods 12. At 13,

I have indicated a foot rail or treadle, at 14 a backrest and at 15 the side arms of the chair coupled with the backrest and braced on the seat by members 16 and front rods 17.

At 18, I have shown a tray which is of more or less conventional form and includes upwardly extending peripheral walls 18a, the purpose of which is to prevent displacement of articles from the tray. In the construction shown, I secure to the inner opposed surfaces of the arms 15 guide channels or tracks 19 in which are slidably mounted upper supporting bars or rods 20. The rods 20 are provided with elongated apertures 21 in which two screws, bolts, pins or the like 22 and 23 operate, the latter also serving to support the channels 19 in connection with the arms 15, and another screw 24 is employed at the inner ends of the channels for the same purpose, the latter also forming stops to limit the inward movement of the rods 20 in said channels so as to position angle iron latch plates 25 carried by and movable with the tray 18 in alignment with spring latch devices 26 supported on the under surface of the arms 15 so that said latch devices can enter apertures 25a in the latch plates 25 to retain the tray against movement with respect to the arms. Brackets 27 are secured to the lower surface of the tray 18 and are pivoted to the forward or outer ends of the rods 20 and detachably coupled therewith by screws or bolts 28 having winged nuts 29. The free ends of the rods 20 also include offset stop members 20a which cooperate with the brackets 27 to limit the swinging movement of the tray 18 to the position indicated in dotted lines in Fig. 1 of the drawing so as to provide clear and unobstructed foot room in the operation of placing a child in the chair and removing the child therefrom.

The purpose of providing the detachable pivots 28 is to facilitate the detachment of the tray from the chair principally in the packing or shipment thereof as well as to facilitate washing or cleaning of the tray whenever desired, and still further, to permit the use of the chair without the tray as a child gets older and is capable of eating directly from a table.

I also secure to the rear end portion of the tray centrally thereof a retaining strap 30, the free end of which is detachably coupled with a suitable coupling device 31 on the lower surface of the seat 10 centrally of the forward edge thereof as is indicated in Fig. 1 of the drawing.

In Fig. 5 of the drawing, I have shown a slight modification wherein I have substituted

for the latch plates 25 on the tray, latch devices 32 similar to the latch devices 26, and these devices are secured to the lower surface of a tray 33 similar to the tray 18, and are adapted 5 to enter apertures 34 formed in channel guide rails 35, otherwise similar in all respects to the rails 19 and in which tray supporting rods 36 similar to the rods 20 are slidably mounted. It will also be noted that the latch devices 32 enter the elongated slots or apertures 37 in the rods 36 and similar to the apertures 21. The spring latch devices 26 and 32 are provided with knobs or finger pieces 26a, 32a, respectively, by means of which the same may be operated by hand to 15 release the tray from its latched position, as will be apparent.

With the construction shown in Figs. 1 to 4 inclusive, and assuming the tray to be in the extended position indicated in dot and dash lines 20 in Fig. 1 of the drawing, after a child has been placed in the chair, the tray is first moved inwardly by sliding the rods 20 in the channel until the free ends of said rods strike the stop pins or screws 24, after which the free end of the 25 tray is swung downwardly to move the latch devices 26 into engagement with the apertures 25a of the latch plates 25, and the strap 30 is then secured in position.

In removing the child from the chair, the 30 strap 30 is first released, after which the latch devices are moved into inoperative position by engaging the knobs 26a and forcing the latch devices outwardly against the tension of their springs. The inner end of the tray is then released by swinging the tray on its pivots 28, after 35 which the tray is moved outwardly, it being understood that the screws, pins or other devices 23 also act as stops to limit the outward swinging movement of the tray or the outward movement 40 of the rods 20, and these pins 23 in conjunction with the pins 22 also serve to brace the rods as well as the tray in their mounting in connection with the arms, that is to say, in addition to the channel guides and supports 19.

45 With the construction shown in Fig. 5 of the drawing the above method of operation can be performed, the only difference being that the latch devices are supported on and movable with the tray. It will be apparent, however, that with 50 this method of latching, the tray may be swung into horizontal position any time that the latch devices 32 are in a position to engage the channels 35, and then the tray may be slid inwardly until such time as said latch devices will extend 55 outwardly into the apertures 34, it being understood that these apertures are preferably disposed at one point to provide the latching of the tray in a desired position. It will be apparent, however, that by employing a number of 60 apertures 34, spaced longitudinally of each rail 35, the tray may be latched in different positions of adjustment.

65 It will be understood that my invention is not necessarily limited to the specific arrangement of the hardware parts employed for slidably and pivotally supporting the tray in connection with the chair, nor to the specific structure of said parts as herein disclosed, and various other changes in and modifications of the 70 invention herein set forth may be made within the scope of the appended claims without departing from the spirit of my invention or sacrificing its advantages.

75 Having fully described my invention, what I

claim as new and desire to secure by Letters Patent, is:

1. In a chair, a tray, means for slidably connecting the tray with the chair to move in a plane substantially paralleling the seat of the chair, and means included in the forward portion of said first named means for pivotally connecting the tray, whereby the tray may be moved into substantially vertical and advanced position.

80 2. In a chair, a tray, means for slidably connecting the tray with the chair to move in a plane substantially paralleling the seat of the chair, means included in the forward portion of said first named means for pivotally connecting the tray, whereby the tray may be moved into substantially vertical and advanced position, the means involving the pivot of the tray being detachable, and means limiting inward and outward sliding movement of said tray with respect to the chair.

85 3. In a chair, a tray, means for slidably connecting the tray with the chair to move in a plane substantially paralleling the seat of the chair, means included in the forward portion of said first named means for pivotally connecting the tray, whereby the tray may be moved into substantially vertical and advanced position, said first named means comprising guide channels and rods slidably engaging said channels, one 90 mounted on the chair and the other on the tray, and means on the rods and at the end portions of the channels for limiting the sliding movement of the rods in both directions with respect to the channels.

95 4. In a chair, a tray, means for slidably connecting the tray with the chair to move in a plane substantially paralleling the seat of the chair, means included in the forward portion of said first named means for pivotally connecting the tray, whereby the tray may be moved into substantially vertical and advanced position, and means for automatically latching the tray to the 100 chair in one position thereof.

105 5. In a chair having arms, the combination with the arms of the chair of a tray, the tray and arms being provided one with elongated channels and the other with members slidably engaging the channels which provide inward and outward sliding movement of the tray with respect to said arms, and means for pivotally mounting the tray 110 in connection with the outer end portion of one of said members to permit swinging movement of the tray into substantially vertical position when the tray is advanced with respect to the 115 arms of the chair.

120 6. In a chair having arms, the combination with the arms of the chair of a tray, the tray and arms being provided one with elongated channels and the other with members slidably engaging the channels which provide inward and outward sliding movement of the tray with respect to said arms, means for pivotally mounting the tray 125 in connection with the outer end portion of one of said members to permit swinging movement of the tray into substantially vertical position when the tray is advanced with respect to the arms of the chair, and means for limiting the swinging movement of said tray.

130 7. In a chair having arms, the combination with the arms of the chair of a tray, the tray and arms being provided one with elongated channels and the other with members slidably engaging the channels which provide inward and outward sliding movement of the tray with respect to said arms, means for pivotally mounting the tray 135 in connection with the outer end portion of one of said members to permit swinging movement of the tray into substantially vertical position when the tray is advanced with respect to the arms of the chair, and means for limiting the swinging movement of said tray.

140 8. In a chair having arms, the combination with the arms of the chair of a tray, the tray and arms being provided one with elongated channels and the other with members slidably engaging the channels which provide inward and outward sliding movement of the tray with respect to said arms, means for pivotally mounting the tray 145 in connection with the outer end portion of one of said members to permit swinging movement of the tray into substantially vertical position when the tray is advanced with respect to the arms of the chair, and means for limiting the swinging movement of said tray.

150

the tray in connection with the outer end portion of one of said members to permit swinging movement of the tray into substantially vertical position when the tray is advanced with respect to the 5 arms of the chair, and interengaging means on said tray and arms for automatically latching the same together against separation.

8. The combination with the arms of a high chair, of channels mounted on the inner faces 10 thereof, rods slidably engaging said channels and

adapted to extend beyond the forward ends of said arms, means for limiting the sliding movement of the rods in both directions in said channels, a tray, and means for pivotally connecting the tray with the forward portion of said rods to provide swinging movement of the tray with respect to said rods when said rods are in extended position.

VICTOR LEIBO.
